UNITED STATES PATENT OFFICE.

GEORGE HORATIO JONES, OF LONDON, ENGLAND.

STOPPER FOR BOTTLES, JARS, AND THE LIKE.

1,076,374.

Specification of Letters Patent.

Patented Oct. 21, 1913.

Application filed April 10, 1913. Serial No. 760,203.

To all whom it may concern:

Be it known that I, GEORGE HORATIO JONES, a subject of the King of Great Britain, residing at London, England, have invented new and useful Improvements Relating to Stoppers for Bottles, Jars, and the like, of which the following is a specification.

My invention relates to improvements in stoppers for securing the contents of bottles, jars and the like, and is designed to enable the vessel to be opened and closed with great rapidity, and to enable a stopper to be constructed at a small cost, which is easily detachable from the bottle or other vessel for washing or other purposes.

My improved stopper is of the kind wherein there is a cap containing an obturating disk which is adapted to be drawn down on to the mouth of the bottle.

According to the present invention, a band or collar is secured around the neck of the bottle and is pivotally secured on one side by means of a link, to the cap. On the other side, the said collar is provided with a cam-lever adapted to engage a link or perforated projection on said cap. This band or collar is divided at the place at which the cap is pivotally attached thereto and the divided ends are connected together by means of the link whereby the band is connected to the cap, this link being curved or otherwise contracted in such a manner that, when the cap is drawn down on to the bottle-mouth, the contracted end of the link holds the divided ends of the band or collar together, but when the bottle is open the ends of the band or collar can be slid apart along one of the longitudinal limbs of the link, so as to allow the band or collar to expand sufficiently to enable it to pass over the shoulder on the bottle neck and so to be removed from the said neck. By this means, the cap together with the band or collar can be readily detached from the bottle when desired, for example, during washing of the latter; or they can be transferred to another bottle having a neck of like form.

The cam-lever may be advantageously made of such form that it is capable of drawing down the link (or perforated projection) on the cap and forcing said link over the lugs on the band or collar to which the lever is pivoted, the said lever being also provided with a tooth, dog or like extension which is adapted to draw the said link off the said lugs when the cam-lever is moved

in the reverse direction. The said lugs on the collar or band can be themselves made cam-shaped, in such a manner that when the link is drawn on to the same, the forces acting on said link will automatically hold it in this position independently of the retaining action of the cam lever, and therefore forms a lock. Or the said lugs may be recessed or notched on the lower side to further assist in retaining the link in position.

The parts of my improved stopper are preferably permanently connected together so that when the stopper is removed from a bottle in use or for washing purposes no part of the said stopper can be accidentally detached from the rest of the stopper and lost.

In the accompanying drawings, I have shown how my said invention may be conveniently and advantageously carried into practice.

In these drawings:—Figure 1 is an elevation of the upper parts of the neck of a bottle showing one form of my improved stopper applied thereto in its closed position. Fig. 2 is an elevation looking in a direction at right angles to that of Fig. 1; and Fig. 3 is an elevation looking in the opposite direction to Fig. 2. Fig. 4 is a corresponding view to Fig. 1 showing the stopper in its open position. Fig. 5 is an underside view showing the permanently connected parts of the stopper detached from a bottle. Fig. 6 is a similar view to Fig. 1 showing a modified form of construction, and Fig. 7 is a plan of the cap thereof.

a is a bottle-neck which is provided with the usual annular projection *b* around it.

c, c are the two halves or sections of a band or collar, which encircles the bottle-neck below the projection *b*. These sections are provided on opposite lugs *d, d* and *e, e*. One pair *d, d* engages with a link *f*, which is pivotally connected at *g* to a sheet-metal cap *h* and is provided with a curved end *f'* of such form as to draw together the lugs *d, d* when the cap *h* is drawn down on to the mouth of the bottle, as shown in Figs. 1 to 3.

The perforated lugs *e, e* are pivotally connected at *e'* to a cam-lever *j*, which engages with an eye or link *k* pivotally mounted on the cap *h*, in order to draw and hold the said link down on to the lugs *e, e* as hereinafter described. This lever *j* is provided with a tooth *m*, which lies beyond the end of the

link *k* on the inside and serves to draw the link *k* off the lugs *e*, *e* when said link is turned in the counter-clockwise direction (Fig. 4).

5 The cap *h* is provided in the interior with a disk of cork *n* or other suitable packing material. The lever *j* is also provided with a perforation *p* to receive a twisted or other wire *q* or other ligament which can be passed 10 around the bottle-neck, the ends being secured by a seal *r*. By this means it is obvious that without cutting the wire or breaking the seal the contents of the bottle cannot be tampered with. This arrangement can be 15 adopted on bottles for wines, spirits, liqueurs and other expensive liquids. In the case of less expensive liquids, a paper or other band can be pasted around the bottle-neck over the lever *j*.

20 Although I use in most cases a flat collar I may employ wire in cheaper constructions.

The operation of my improved stopper, is as follows:—Assuming the bottle to be open, as shown in Fig. 4, the cap *h* is swung on to 25 the mouth of the bottle and the lever *j* passed through the loop of the link *k* and then turned in a clockwise direction, so as to force the said link on to the lugs *e*, *e*, as shown in Figs. 1 and 2. The cap *h* is then 30 securely held on the bottle-mouth, since the lugs *e*, *e* are made of such form that there is no tendency for the link to move off them under vibration. When the lever *j* is turned in the reverse direction, the tooth *m* thereon 35 draws the link *k* off the lugs *e*, *e*, so that the cap *h* can be readily removed from the bottle-mouth. If it be desired to detach the stopper entirely from the bottle, the link *f* is moved into the position shown in Fig. 5 40 relatively to the lugs *d*, *d*. These lugs can then move apart, so as to allow the band *c*, *c* to open and pass over the projection *b* on the bottle neck.

In the modified form of construction 45 shown in Figs. 6 and 7, the cap *h* is made with lugs *o*, *o*, formed integrally therewith and the lever *j'* is curved in the reverse direction to the lever *j* in Figs. 1 and 4.

I claim:

50 1. A stopper for bottles and jars, said stopper comprising a cap, a collar for extending around the neck of the vessel to be closed and divided on one side, a link pivotally connected to said cap and extending 55 through apertures in the ends of the collar at the division and provided with a limb along which said ends can slide apart and with a closed end for holding said ends positively together in the closing of the vessel, 60 and means for detachably connecting the other side of said collar to said cap.

2. A stopper for bottles and jars, said stopper comprising a cap, a collar for ex-

tending around the neck of the vessel to be closed and divided on one side, a link pivotally connected to said cap and extending 65 through apertures in the ends of the collar at the division and provided with substantially parallel limbs, along one of which said ends can slide apart, and with a closed end 70 for drawing and holding said ends of the collar positively together in the closing of the vessel, a cam-lever pivotally mounted in lugs on the other side of said collar, and an eye on said cap for engaging said cam-lever 75 and said lugs.

3. A stopper for bottles and jars, said stopper comprising a cap, a collar for extending around the neck of the vessel to be closed and divided on one side, a link pivotally connected to said cap and extending 80 through apertures in the ends of the collar at the division and provided with a closed end for drawing and holding said ends positively together in the closing of the vessel, a 85 cam-lever pivotally mounted in lugs on the other side of said collar, an eye on said cap for engaging said cam-lever and said lugs, and a tooth on said cam-lever, for removing 90 said eye from said lugs.

4. A stopper for bottles and jars, said stopper comprising a cap, an obturating disk in said cap, a collar for extending around the neck of the vessel to be closed and divided on one side, a closed link pivotally connected to said cap and extending through 95 apertures in the ends of the collar at the division, said link having a closed end for holding said ends of the collar together in the closing of the vessel, a cam-lever pivoted 100 in lugs on the other side of said collar, and an eye pivotally mounted on said cap and adapted to engage said cam-lever and said lugs.

5. A stopper for bottles and jars, said 105 stopper comprising a cap, an obturating disk in said cap, a collar for extending around the neck of the vessel to be closed and divided on one side, a closed link pivotally connected to said cap and extending 110 through apertures in the ends of the collar at the division, said link at its free end drawing and holding said ends of the collar together in the closing of the vessel and having substantially parallel limbs along one 115 of which the ends of the collar can slide apart, a cam-lever pivoted in lugs on the other side of said collar, an eye pivotally mounted on said cap and adapted to engage said cam-lever and said lugs, and a tooth on 120 said cam-lever for removing said eye from said lugs.
